UNITED STATES PATENT OFFICE.

ISAAC W. NUMAN, OF CANTON, OHIO.

HAME-TUG ATTACHMENT.

SPECIFICATION forming part of Letters Patent No. 271,260, dated January 30, 1883.

Application filed July 17, 1882. (No model.)

To all whom it may concern:

Be it known that I, ISAAC W. NUMAN, a citizen of the United States, residing at Canton, in the county of Stark and State of Ohio, have invented certain new and useful Improvements in Hame-Tug Attachment and Adjusting Device, of which the following is a specification, reference being had therein to the accompanying drawings.

10 Figure 1 is an outside view of one of my improved tug attachments. Fig. 2 is a perspective view of the casing and the metal strengthening-strips. Fig. 3 is a perspective view of the last said parts in the positions occupied when put together. Fig. 4 is a section on line $x-x$, Fig. 1. Figs. 5, 6, and 7 are perspectives of details. Figs. 8 and 9 are outside views of slightly-modified forms. Fig. 10 is a section on line $y-y$, Fig. 9. Fig. 11 is an enlarged view 20 of a part of Fig. 10.

This invention relates to improvements in adjustable hame-tugs of the kind represented broadly in my Patent No. 254,683, dated March 25, 1882. In said patent I showed and described a tug-adjusting device consisting of a skeleton metal frame having a screw-rod mounted therein for moving the end of the tug forward and back; but I have found that for some purposes an adjusting mechanism of the character set 30 forth in said patent is of an inferior nature, especially where frequent adjustment is required, and where the adjustment must be over comparatively long distances, inasmuch as the threaded rod must be rotated a considerable 35 number of times to produce the requisite movement. Moreover, the skeleton-frame shown in said patent I find to be more expensive and heavier than is desirable for some kinds of harness.

40 This invention relates to a tug attachment and adjusting device having an inclosing-case which, while being lighter than the skeleton-frame and less expensive, is nevertheless as strong, and is adapted to permit the forward 45 end of the tug to move with more freedom than when a frame is used of the character shown in said patent.

To this end the invention consists in forming a hollow case having continuous walls on all sides, so as to form a chamber, within which the forward end of the tug is received and con-

cealed. As the casing is made continuous on all sides, it may be made of much lighter and cheaper material than when a solid, heavy skeleton metal frame is employed.

55 The invention relates, further, to a mechanism for speedily and readily adjusting the tug, and relates, also, to various matters which will be fully described and set forth in detail hereinafter.

60 In the drawings I have shown my invention as applied to a hame-tug in several modified ways, though it will be readily understood, after an examination of the drawings and the following description, that in matters of detail 65 the device may be varied without departing essentially from the invention.

The supporting and concealing casing is represented by A. This is made with continuous walls on all sides, so as to form a hollow chamber. As the material of which it is composed extends continuously all around, it may be made of a light material, such as tin or other thin metal or wood, and I have found that papier-maché even may be used successfully 70 for this purpose. This is covered with leather, which is arranged to form a tight jacket around it, the leather being kept in form and shape by the casing within. The casing provides an open chamber, within which the forward end 75 of the tug can move freely, there being none of the cramping or binding that is experienced when the end of the tug is compressed tightly between flexible parts. At the forward end the tug is provided with an eye, C, for fastening 80 it to the hames. This eye is secured in place in the casing by means of one or more screws or rivets passing through from one side of the casing to the other, as shown at c. The supporting part C' of the eye-piece has an inner 85 stem or shank, C², which is seated within the end of the casing to support the edges at the end, and has also an expanded part, c', which may be made ornamental for providing a strong closing-piece and cover for the edges 90 and end of the casing.

95 The tug is represented by D. It is provided with a series of perforations, d d, near its forward end. Said end is adapted to slide in and out of the casing A at the rear open end. When the length of the tug is to be changed 100 it is moved in or out far enough to bring the

proper aperture *a* opposite to the apertures *a'*, which are formed in the side of the casing *A*. Through these apertures there passes a pin, *E*, adapted to go through the tug. The pin is prevented from seriously wearing or straining the casing or the leather covering thereof by means of an eyelet, *E'*, fastened in the aperture *a* and an eyelet, *E²*, in the aperture *a'*. With the pin there is combined a locking device adapted to prevent its being accidentally withdrawn. The form of lock which I prefer is shown in the drawings at *F*, it consisting of a sliding bolt seated beneath the plate *E³*, which latter is preferably formed in one piece with the eyelet or part *E²*.

Having thus described what I consider the essential features of my invention, I will now set forth the devices which may be combined therewith to make a still more advantageous *tug attachment and adjusting mechanism*. Thus the hollow light casing may be strengthened by means of two strips, *G G*, of steel, opposed to each other—that is, placed upon opposite sides of the casing and secured thereto by rivets. When the casing (strong enough of itself under ordinary circumstances by having the walls continuous) is supplemented by these metal strips there is produced a very durable tug attachment, capable of withstanding the most serious strain and wear. Again, I prefer to attach the pin *E* to a flat metal spring, *H*, so that it shall automatically pass through the apertures and tend to be held by the spring in place. *I* is a leather cover, situated behind the spring *H*, to form a facing or jacket for it, so that the horse shall not be affected by the metal of the spring. The leather preferably extends beyond the spring, as shown at *i*, to form a convenient flexible handle to pull the spring back.

In Fig. 7 I have shown an improved form of a loop or buckle to be combined with the casing and the tug. It is constructed in two parts, one consisting of the back plate, *J*, the upper loop, *J'*, the lower loop, *J²*, the end loop, *J³*, and the arms *J⁴ J⁴*, provided with rivet pieces *j j*, and the other part consisting of a cross-bar, *J⁵*, provided with perforations at the ends adapted to fit upon and be riveted against the arms *J⁴*.

At *j' j* the back plate is riveted to the inner hollow casing, *A*. It is cut away or provided with a recess, *J⁶*, which permits the pin *E* to be readily inserted and withdrawn, and also allows the spring *H* to lie close to the casing.

Heretofore the loops or buckles corresponding to those just described have been secured to the leather parts by means of stitching; but for heavy harness I find this method of riveting the loop or buckle to the attachment casing to be much better. The cross-bar *J⁵* of this loop or buckle may be perforated at the center, so that the central part thereof shall act as the eyelet *E²*. With it also may be formed integrally the plate *E³*, beneath which lies the lock *F*. This latter is preferably made

of a wire or rod bent to have the outwardly-projecting part *f*, (in the slot *f'*,) by which it can be moved back and forth. There is a groove in the under side of the plate, which operates as a guide for the lock. The pin *E* is provided with an aperture, into which the lock passes, though a slot may be used instead of the aperture, if desired.

In Fig. 10 I have shown the tug attachment in the form in which I prefer to make it for use with breast-collars. The manner of securing it to the collar will be readily understood.

It will be seen that the hollow casing *A* provides a strong support for the eye-piece *C* for the spring which carries the locking-hinge and for the loops at the rear end, all of which are formed separately from the casing and riveted or otherwise secured thereto. The casing insures that all of the parts of the tug attachment shall be held constantly in substantially the same position relatively to each other, and is therefore much better than the casing devices which have been made of leather, and therefore liable to stretch so as to vary the positions of the parts.

What I claim is—

1. The herein-described tug attachment, consisting of the eye-piece *C*, the pin *E*, which fastens the tug and is held in place independently of the tug, and the devices for preventing accidental withdrawal of the pin from the tug, in combination with the hollow casing *A*, having continuous walls on all sides, and formed separately from said eye-piece *C* and pin *E*, and connected, substantially as set forth, to the devices which hold pin *E*, whereby straining of the leather parts is prevented and a concealing-chamber is provided for the forward end of the tug. 105

2. The combination, with the hollow casing *A*, of the tug provided with a series of perforations at its end, the pin *E*, the perforated plates or eyelets *E' E²* in the walls of the casing *A*, and means for preventing the withdrawal of said pin, substantially as set forth. 110

3. The combination, with the casing, the hame-tug provided with perforations, and the pin adapted to pass through the perforations, of the spring permanently secured to said pin, 115 substantially as set forth.

4. The combination of the casing, the tug provided with perforations, and the pin *E* with the spring and the leather covering for said spring, extended beyond the end thereof to form a flexible handle, substantially as set forth. 120

5. The combination of the hollow casing having continuous walls on all sides, the eye *C*, formed separately from and rigidly secured to said casing, the pin *E*, passing through the rear end of the casing from one side to the other, the lock *F*, the plate *E³*, secured to one side of the casing, and the devices which prevent accidental withdrawal of the pin *E* after it is unlocked, secured to the casing on the side opposite to the lock, substantially as set forth. 125 130

6. The combination of the casing and the pin E for engaging with the tug, and the sliding lock F, arranged to engage with the pin, substantially as set forth.
- 5 7. The combination of the casing, the tug, the pin adapted to engage with the tug, the eyelet E², formed with the slotted plate F³, and the sliding lock beneath said plate, substantially as set forth.
- 10 8. The combination, with the casing, the buckle at the rear end having a loop above, the loop below, and the loop at the end of the buckle, and riveted to the casing, of the cross-bar J⁵, riveted to arms projecting from the buckle, substantially as set forth. 15

In testimony whereof I affix my signature in presence of two witnesses.

ISAAC W. NUMAN.
